UNITED STATES PATENT OFFICE.

KAZUO KODAMA, OF PETERSBURG, TERRITORY OF ALASKA.

SOAP CASE.

Application filed February 8, 1928. Serial No. 252,891.

This invention relates to new and useful improvements in soap cases and aims to provide a novel and simple case for containing a cake of soap and that is so constructed as 5 to permit the soap to be easily removed therefrom without straining the fingers, or without turning the case upside down, which is necessary in practically all cases now in use.

10 In carrying out the invention the case consists of a suitable container of a shape generally similar to the shape of the cake of soap to be disposed therein, said container being equipped with a pivotal soap supporting wall that will permit the cake of soap to 15 be tilted within the case so that it will partially project therefrom, permitting the same to be readily removed.

One of the most important objects of the 20 invention is to provide a soap case of this character that is exceedingly simple in construction and one that is very useful.

In the drawings wherein like reference characters indicate corresponding parts 25 throughout the several views:

Figure 1 is a side elevation of my improved soap case, the lid being removed and the cake of soap being disclosed in the act of being removed therefrom.

30 Figure 2 is a top plan view of the case, the lid being open, and

Figure 3 is a detail longitudinal section of the case, said lid being removed, or in open condition.

35 Now having particular reference to the drawing, my novel soap case consists of a container 5 of suitable material, and of predetermined size and shape, the shape of the same preferably being similar to that of a 40 cake of soap A arranged therein. Arranged transversely within this container 5 is a pivot pin 6 intermediate the end walls of the case and slightly beneath the center thereof as disclosed in Figures 1 and 2. Arranged 45 within the container 5 above said pivot 6 is a

plate 7 of an area such as to permit the tilting of the same within the container as indicated by the dotted lines in Figure 1. The bottom surface of this plate 7 is equipped 50 with a transverse sleeve 8 through which the pivot 6 passes which obviously serves as a pivotal connection between the plate and said pivot pin.

Surrounding the pivot 6 at opposite sides 55 of the plate carrying sleeve 8 are coil springs 9-9, the same being wound in opposite di-

rections. The inner ends of the springs extend toward the opposite end walls of the container 5 and have engagement with the under side of the plate by reason of their own inherent qualities. The outer ends of these springs 9-9 extend downwardly and are connected to a cross pin 10 arranged transversely through the container 5 directly beneath the pivot pin 6. Obviously these 60 springs 9-9 serve to normally maintain the plate 7 in horizontal position within the container as more clearly disclosed in Figure 3. Obviously however when a cake of soap A is disposed thereon, pressure against either 65 end of the cake of soap will cause the tilting of the plate and the consequent projection of the opposite end of the soap from the container so that the soap may be removed 70 readily therefrom.

The container 5 may be, and preferably is equipped with a suitable lid 11 either of the hinged type, slip type or the like.

In view of the foregoing description when considered in conjunction with the accompanying drawing it will be apparent that I have provided a highly novel, simple, and extremely useful soap case that is well adapted for all the purposes heretofore designated, even though I have herein shown 80 and described the invention as consisting of certain detail structural elements it is nevertheless to be understood that some changes 85 may be made therein without affecting the spirit and scope of the appended claims.

Having thus described my invention, what I claim as new and desire to secure by Letters Patent is:—

1. In a soap holder of the class described, an open top container, a soap supporting 95 plate pivotally supported within the container at its intermediate portion, a transverse rod on which said plate is pivotally mounted, a pair of axial coil springs encircling said rod and being wound in opposite directions, the inner ends of the springs being disposed laterally in opposite directions for engagement with the opposite side of the plate, the outer ends of the axial coil springs being disposed downwardly and secure to the container, said springs normally maintaining 100 the plate in a horizontal position.

2. In a soap holder of the class described, an open top container, a rod extending 110 transversely between the sides of the container at the central portion thereof, a soap supporting plate, a sleeve carried by the

under side of the intermediate portion of said plate and disposed transversely with respect thereto for receiving said rod whereby the plate is pivotally supported in the container, a pair of oppositely wound axial coil springs encircling said rod at the opposite sides of the sleeve, the inner ends of these springs being disposed laterally in opposite directions for engagement with the under side of the horizontal plate,

the outer ends of the axial coil springs being disposed downwardly, and an additional rod extending transversely between the sides of the container below the first mentioned rod to which the free ends of the depending portions of the springs are connected, said springs normally holding the plate in a horizontal position in the container. 15

In testimony whereof I affix my signature.

KAZUO KADAMA.
